OTTO E. BILLGREN, OF JERSEY CITY, NEW JERSEY

PIPE STAND AND CLEANER

Application filed March 5, 1931. Serial No. 520,310.

My invention relates to a combined pipe stand and pipe cleaner. The object of the invention is to make a combined pipe stand and pipe cleaner from a single piece of sheet

5 metal, which is cheap to manufacture and readily adapted to practically all kinds of pipes commonly used.

My invention will be understood by reference to the accompanying drawing taken 10 in conjunction with the following description, which drawing is to be considered as a part of this specification.

With reference to the drawing:

Fig. 1 shows a metal blank cut to form 15 for making my improved pipe stand and cleaner;

Fig. 2 is an end view of the pipe stand and cleaner;

Fig. 3 is a top view thereof; and 20 Fig. 4 is a perspective view.

The pipe stand and cleaner is made of sheet metal by first stamping a blank as shown in Fig. 1, designated generally by reference character 10. The blank comprises 25 a central portion 11 having relatively long wings 12, an end portion 13, which is tapered, and an end portion 14 having relatively short lateral projections 15.

This blank having been made, the pipe 30 stand and cleaner is formed by curving the wings 12 upwardly so that they may embrace a pipe stem as shown in Fig. 4 and bending the projections 15 downwardly to form feet. This is preferably done in a one 35 machine operation, in which the end portion 13 is also preferably curved slightly to embrace the lower portion of a pipe stem.

The material is thin metal and can be readily bent and adapted to any straight pipe 40 stem and to some curved pipe stems.

The end portion 13 constitutes a cleaner for 45 cleaning tobacco out of a pipe, the portions 11 and 14 being in this respect a handle. It will be seen that the pipe stand and cleaner 50 can be left on the pipe except when it is being used as a cleaner, and that it will not disturb the handling of the pipe by the smoker. If desired the edges of the end portion may be sharpened or tapered more or less to facilitate digging tobacco out of the pipe. 55

It will be seen that, as a pipe stand, my novel device is particularly adaptable to support pipes which have a tendency to roll sideways.

What I claim is:

1. A pipe stand and cleaner having a central portion with upturned wings for embracing the stem of a pipe, an end portion having downturned feet, and an end portion providing a cleaning blade. 60

2. A pipe stand and cleaner made of a single piece of sheet metal and having a central portion with upturned wings for embracing the stem of a pipe, an end portion having downturned feet and an end portion providing a cleaning blade, said central portion and said end portions being transversely bent to give a curved surface. 65

3. A pipe stand and cleaner having a central portion with upturned wings for embracing the stem of a pipe, an end portion having supporting means, and an end portion providing a cleaning blade. 70

In testimony whereof I have affixed my signature. 75

OTTO E. BILLGREN.
